COLLAR CAN COLLAR STRUCTURE

John Coyle, Baltimore, Md., and Jacob F. Egenolf,
New York, N. Y., assignors to Continental Can
Company, Inc., New York, N. Y., a corporation
of New York

Application April 3, 1945, Serial No. 586,296

5 Claims. (Cl. 220—61)

1

The invention relates generally to metallic receptacles, and more particularly to the type known as collar cans wherein are provided tear strips adapted to be wound on keys and by this means torn out of the body walls of the cans in order to effect an opening thereof, and it primarily seeks to provide a novel collar structure for such cans.

In cans of the type stated the tear strips usually are defined by parallel score lines which surround the cans adjacent the upper ends thereof, and a collar is snugly fitted within the upper end of each can in position for extending upwardly from the upper extremity of the can body resulting from the tearing out of the rip strip, thereby to maintain the desired can body wall height and provide a support neck over which the skirt or body wall portion remaining attached to the upper end closure can be telescoped to effect a reclosure of the can. Such collars usually are formed of metal strips or bands formed into circular shape, and it is desirable to curl or curl and hem the upper and lower edge extremities in order to avoid presentation of raw metal edge portions and also to impart rigidity to the collar structure. However in such structures it has been found difficult to provide the necessary strip or band end overlap and yet maintain a close fit of all parts of the collar against the can body wall and avoid provision of objectionable multiple thickness bulk at overlapped portions.

Therefore, it is an object of the present invention to provide a collar of the character stated in which the strip or band has its upper and lower edge portions curled and hemmed respectively and its overlapped upper and lower end edge portions provided with interfitting tongues and notches cooperating to securely retain the overlapped engagement and avoid provision of objectionable multiple thickness at the overlapped portion, and also to provide smooth exterior of the curl without objectionable external surface projection throughout the circle of the collar and a smooth substantially continuous cylindriform exterior of the collar adapted for snugly engaging within the container body.

With the above and other objects in view that will hereinafter appear, the nature of the invention will be more clearly understood by reference to the following detailed description, the appended claims, and the several views illustrated in the accompanying drawing.

In the drawing:

Figure 1 is a side elevation of a can structure in-

2

cluding a collar embodying the invention, parts being broken away and in section.

Figure 2 is a face view of the two end portions of a band from which the collar is formed, the outer faces of the band end being shown.

Figure 3 is a fragmentary perspective view illustrating the band ends shown in Figure 2, the upper edge portion of said band ends being curled.

Figure 4 is a fragmentary perspective view illustrating the overlapped and interlocked end portions of the band from which the collar is formed.

Figure 5 is a horizontal section taken on the line 5—5 on Figure 4.

Figure 6 is a detailed vertical cross section taken on the line 6—6 on Figure 4.

Figure 7 is a detail vertical cross section taken on the line 7—7 on Figure 4.

In this disclosure the invention is illustrated as embodied in a can including a body 5, a lower end closure 6, and a top end closure 1, said closures preferably being seam-secured on the can body in the conventional manner.

The can body 5 is provided adjacent its upper end with an inwardly directed rest bead 8 preferably provided as a support for the lower, hem equipped edge 9 of the improved collar structure generally designated 10 and which is equipped with an inwardly directed curl 11 at its upper edge portion. Opposite the main body portion of the collar 10 the can body is annularly scored in the conventional manner to provide a tear strip 12 adapted to be wound about a key and torn from the wall of the can body in the manner well known in the art for effecting an opening of the can.

According to the invention, the collar generally designated 10 is formed from a strip or band of metal having the upper and lower edge portion of its ends shaped in the manner illustrated in Figure 2, it being understood that these ends are brought together and overlapped to provide the desired shape of collar intended to snugly fit within the can body in which the collar is to be incorporated. While these collars are most commonly incorporated in cylindrical containers, it is to be understood that the collar structure disclosed herein can be incorporated in oval shaped can bodies or in can bodies otherwise shaped, such as square or oblong structures having rounded corners.

In the completed collar structure the band ends are overlapped as at 13 as indicated in Figures 1, 4 and 5 of the drawing, and it will be noted by reference to Figure 2 that one end of the band at 55 the upper edge is provided with a plurality of

spaced notches 14 providing intervening spaced tongues 15 of like width and which are intended to fit in spaced notches 16 formed in the upper edge portion of the other end of the band and which provide intervening tongues 17 of like width intended to fit in the previously mentioned notches 14.

It will also be apparent by reference to Figure 2 that the lower edge portion of the band at one end is equipped with a plurality of edge notches 18 providing intervening tongues 19 of like width intended to engage in spaced notches 20 formed in the lower edge of the other end of the band and which provide intervening tongues 21 of the like width intended to engage in the previously mentioned notches 18.

When the bands are overlapped in the manner illustrated in Figures 1, 4 and 5 and the upper edge tongues 15 and 17 are interlocked in the receiving notches 16 and 14, the edges of said tongues snugly engage at 22 and the lower tongues 19 and 21 interlock in the respective notches 20 and 18 and snugly engage in edge contact as at 23. In this manner the upper edge curl 11 has substantially smooth exterior without objectionable external surface projection about the whole circle of the collar in the manner clearly illustrated in Figures 1, 4, 6 and 7. The hem is formed by folding over the lower edge portion of the band substantially along the dot and dash line indicated at L in said figure. See also Figure 4.

It will be apparent by reference to Figures 4 and 5 of the drawing that the inwardly overlapped band end portion is offset to the extent of its thickness as at 24 thereby to dispose the remainder of the band to snugly engage the body wall of a can in which the collar is inserted throughout the continuity of the collar in the manner clearly illustrated in Figure 5.

It will be apparent that the interlocking tongues 15, 17 and 19, 21 will secure the overlapped band ends against separation in a circumferential direction, and the folding of the tongue and edge portions of the outermost lapped band and inwardly and upwardly over the innermost lapped band end in the manner illustrated in Figure 6 secures the lapped band ends against separation in the radial direction.

It will be apparent that throughout the circumference of the collar a single thickness of metal is provided except at the two thicknesses provided at the overlapped main body ends and the three thicknesses provided at the position of the interlocked tongues 19, 21.

While one form of the invention has been shown for purposes of illustration, it is to be clearly understood that various changes in the details of construction and arrangement of parts may be made without departing from the spirit and scope of the invention as defined in the appended claims.

We claim:

1. A collar for a collar can, said collar having upper and lower edge portions disposed in parallel relation throughout the whole circumference of the collar and comprising a band shaped to fit within a can and having its ends overlapped flatwise, the overlapped ends of the band at one edge portion having complementary interlocking notches and tongues with the tongues of each overlapped end at said one edge portion disposed to engage in the notches of the other overlapped end at said one edge portion with the tongues engaging in edge to edge contact, said

one edge portion of the band including the interlocked tongues thereof being formed into a curl having a smooth exterior devoid of external surface projections throughout the circumference of the collar, and means securing the overlapped ends against separation in the radial direction.

2. A collar for a collar can, said collar having upper and lower edge portions disposed in parallel relation throughout the whole circumference of the collar and comprising a band shaped to fit within a can and having its ends overlapped flatwise, the overlapped ends of the band at one edge portion having complementary interlocking notches and tongues with the tongues of each overlapped end at said one edge portion disposed to engage in the notches of the other overlapped end at said one edge portion with the tongues engaging in edge to edge contact, said one edge portion of the band including the interlocked tongues of the innermost lapped end being folded upon itself and the tongues of the outermost lapped end being bent against the inner face of the innermost lapped end in the form of an edge reinforcing hem to prevent separation of the lapped ends in the radial direction.

3. A collar for a collar can, said collar having upper and lower edge portions disposed in parallel relation throughout the whole circumference of the collar and comprising a band shaped to fit within a can and having its ends overlapped flatwise, the overlapped ends of the band at one edge portion having complementary interlocking notches and tongues with the tongues of each overlapped end at said one edge portion disposed to engage in the notches of the other overlapped end at said one edge portion with the tongues engaging in edge to edge contact, said one edge portion of the band including the interlocked tongues thereof being formed into a curl having a smooth exterior devoid of external surface projections throughout the circumference of the collar, and the overlapped ends of the band at the other edge portion having complementary interlocking notches and tongues with the tongues of each overlapped end at said other edge portion disposed to engage in the notches of the other overlapped end at said other edge portion with the tongues engaging in edge to edge contact, and said other edge portion of the band including the interlocked tongues of the innermost lapped end being folded upon itself and the tongues of the outermost lapped end being bent against the inner face of the innermost lapped end in the form of an edge reinforcing hem to prevent separation of the lapped ends in the radial direction.

4. A collar for a collar can, said collar having upper and lower edge portions disposed in parallel relation throughout the whole circumference of the collar and comprising a band shaped to fit within a can and having its ends overlapped flatwise, the overlapped ends of the band at one edge portion having complementary interlocking notches and tongues with the tongues of each overlapped end at said one edge portion disposed to engage in the notches of the other overlapped end at said one edge portion with the tongues engaging in edge to edge contact, said one edge portion of the band including the interlocked tongues thereof being formed into a curl having a smooth exterior devoid of external surface projections throughout the circumference of the collar, the inwardly overlapped band end being

offset to the extent of its thickness thereby to dispose the remainder of the band for snug engagement with the body wall of a can in which the collar is inserted throughout the continuity of the collar, and means securing the overlapped ends against separation in the radial direction.

5. A collar for a collar can, said collar having upper and lower edge portions disposed in parallel relation throughout the whole circumference of the collar and comprising a band shaped to fit within a can and having its ends overlapped flat-wise, the overlapped ends of the band at one edge portion having complementary interlocking notches and tongues with the tongues of each overlapped end at said one edge portion disposed to engage in the notches of the other overlapped end at said one edge portion with the tongues engaging in edge to edge contact, said one edge portion of the band including the interlocked tongues thereof being formed into a curl having a smooth exterior devoid of external surface projections throughout the circumference of the collar, and the overlapped ends of the band at the other edge portion having complementary interlocking notches and tongues with the tongues of each overlapped end at said other edge portion disposed to engage in the notches of the other overlapped end at said other edge portion with the tongues engaging in edge to edge contact, and said other edge portion of the band including the interlocked tongues of the innermost

lapped end being folded upon itself and the tongues of the outermost lapped end being bent against the inner face of the innermost lapped end in the form of an edge reinforcing hem to prevent separation of the lapped ends in the radial direction, the inwardly overlapped band end being offset to the extent of its thickness thereby to dispose the remainder of the band for snug engagement with the body wall of a can in which the collar is inserted throughout the continuity of the collar.
